UNITED STATES PATENT OFFICE

91,521

DESIGN FOR A COMBINED VESSEL AND COVER FOR ELECTRIC COOKER

Marshall W. Hanks, Madison, Wis.

Application November 9, 1933. Serial No. 49,683

Term of patent 3½ years

To all whom it may concern:

Be it known that I, MARSHALL W. HANKS, a citizen of the United States, residing at Madison, in the county of Dane and State of Wisconsin, have invented a new, original, and ornamental Design for a Combined Vessel and Cover for Electric Cooker, of which the following is a specification, reference being had to the accompanying drawing, forming a part hereof.

The figure is a perspective view of a combined vessel and cover for electric cooker showing my new design.

I claim:

The ornamental design for a combined vessel and cover for electric cooker, as shown.

MARSHALL W. HANKS.
